US00D637657S

(12) **United States Design Patent**
Zivanovic

(10) **Patent No.:** **US D637,657 S**
(45) **Date of Patent:** **** May 10, 2011**

(54) **STEERING WHEEL LOCK**

(76) Inventor: **Slobodan Zivanovic**, Mississauga, CA
(US)

(**) Term: **14 Years**

(21) Appl. No.: **29/366,198**

(22) Filed: **Jul. 21, 2010**

(51) **LOC (9) Cl.** **21-01**

(52) **U.S. Cl.** **D21/333; D14/414**

(58) **Field of Classification Search** **D21/324, D21/333, 385, 417, 566; D14/400, 412, D14/414, 416, 432; 273/148 B, 449, 441, 273/442; 434/45, 46; 463/1, 28-38, 46, 463/47; 70/209, 226, 237, 238**
